DESIGN FOR AN INDUSTRIAL TRACTOR

Carl W. Sundberg and Montgomery Ferar, Detroit, Mich., assignors to Clark Equipment Company, Buchanan, Mich., a corporation of Michigan

Application April 27, 1939, Serial No. 84,598

Term of patent 14 years

To all whom it may concern:

Be it known that we, Carl W. Sundberg and Montgomery Ferar, citizens of the United States, residing at Detroit, in the county of Wayne and State of Michigan, have invented a certain new, original, and ornamental Design for an Industrial Tractor, of which the following is a description, reference being had to the accompanying drawings, forming a part thereof:

In the drawings:

Figure 1 is a side elevational view of an industrial tractor embodying our new design;

Figure 2 is a front perspective view of the tractor shown in Figure 1; and

Figure 3 is a rear elevational view of the tractor.

We claim:

The ornamental design for an industrial tractor, as shown.

CARL W. SUNDBERG,
MONTGOMERY FERAR.
